UNITED STATES PATENT OFFICE.

GEORGE B. COX, OF WRAY, COLORADO.

RAILROAD TIE.

Application filed January 16, 1925. Serial No. 2,912.

To all whom it may concern:

Be it known that I, GEORGE B. Cox, a citizen of the United States of America, and resident of Wray, in the county of 5 Yuma and State of Colorado, have invented a new and Improved Railroad Tie, of which the following is a full, clear, and exact description.

This invention has relation to railroad 10 ties and has particular reference to metal ties, the same being in the nature of an improvement upon my copending application Serial No. 732,456 filed August 16, 1924.

One of the principal objects of the present 15 invention is to generally improve and simplify the structure of the tie set forth in my copending application for reducing to an absolute minimum the number of parts composing the same and this without 20 in any way detracting from the general efficiency or strength of the tie.

The present invention broadly comprehends a rail tie consisting of a pair of interfitting sections which function to support and securely clamp the rails in properly spaced relation, thereby eliminating the time and labor required for the spiking operation as well as the dangers incident 25 to the possibility of accidental displacement 30 of the spikes and facilitating the removal and replacement of the ties.

With the above recited and other objects in view, the invention resides in the novel construction set forth in the following 35 specification, particularly pointed out in the appended claims and illustrated in the accompanying drawings, it being understood that the right is reserved to embodiments other than those actually illustrated herein 40 to the full extent indicated by the general meaning of the terms in which the claims are expressed.

In the drawings—

Figure 1 is a longitudinal sectional view 45 through a tie constructed in accordance with the invention, said section being taken approximately on a line indicated at A—A in Fig. 3.

Fig. 2 is a transverse sectional view taken 50 approximately on the line indicated at 2—2 in Fig. 1.

Fig. 3 is a top plan view of the tie.

Fig. 4 is a collective perspective view of 55 the tie elements or sections disassociated from each other.

Referring to the drawings by characters

of reference the tie comprises a pair of substantially identical sections A and B which are preferably formed of sheet metal, rolled or otherwise constructed. The sections 60 each consist of a substantially channel-shaped member or of inverted U-shape in cross section providing an upper horizontal wall 10 and parallel depending side walls 11 at the lower free end of which laterally projecting horizontal flanges 12 are provided the outer end portions 13 of which flanges are of greater width than the remaining portion to provide a greater foot- 65 ing or bearing surface immediately below 70 the point at which the weight of the rolling stock is received. The upper horizontal wall 10 of the section A is of slightly greater width than the corresponding wall 75 of section B and the side walls 11 of the section A are spaced apart a distance slightly greater than the distance between the walls 11 of section B whereby the section A may telescopically receive the section B. 80 At the inner end, each section is recessed or cut away as at 14 to conform in shape to at least one side of a standard rail illustrated at R. In other words, the inner ends of the sections are so shaped as to provide relatively low upstanding webs 15 upon 85 which the rail base bears and further, this shaping of the inner ends of the sections provides rail engaging web tongues 16. Adjacent the outer end of each section, recessed portions 17 are provided which produce relatively low upstanding webs 18 having overhanging inwardly projecting web engaging tongues 19 at the outer end of the recessed portion. Under this construction when the sections are mated or 90 telescopedically engaged, the recessed portions together with the overhanging web engaging tongues 16 and 19 constitute a rail supporting and clamping means. In order to 95 provide means for positively retaining the sections A and B in clamping relation to the rails, the medial portions of the depending side walls 11 are provided with longitudinal slots 20 which are disposed in substantial alinement when the sections are in 100 clamping relation to the rails and through which a wedge key 21 is driven.

In initially laying a track, the sections are shifted relatively outward or laterally away from each other so that the overhanging web engaging tongues 16 are retracted 105 wholly within the channel member of the

opposite section to leave the recesses 17 open or clear for the reception of the rails R. The outer side portion of each rail base flange is engaged beneath the overhanging 5 web engaging tongue 19 and rests upon the upper edge of the low upstanding webs 18. The sections are then relatively shifted inwardly toward each other so that the tongues 16 are projected from the opposite channel 10 member to overlîe the inner sides of the base flanges of the rails and abut with the rail webs at their inner side surfaces. The wedge key 21 is then driven in place through the slots 20 and the attachment of the rails to 15 the ties is completed. It will thus be noted that the rails are supported upon the upper edges of the low web portions 15 and 18 while the same are properly spaced apart, clamped and locked in position. When for 20 any reason it is desired to remove or replace a tie, the wedge key is removed and the sections A and B are shifted relatively outward at the same time lowering the tie by removing a portion of the roadbed or ballast 25 to allow for the lowering movement. When the upper wall 10 of the section A is disposed in a plane below the lower base flanges of the rails it is obvious that the sections may be respectively separated laterally to 30 completely remove the tie.

From the foregoing it will thus be seen that a rail tie has been provided which eliminates the necessity of the use of spikes and which efficiently functions to support, properly space and clamp the rails when in applied position.

I claim:

1. A rail tie comprising a pair of telescopically associated inverted substantially 40 U-shaped sections, each of said sections having a recessed inner end and complementary recessed portions adjacent its outer end adapted to respectively coact with each other upon inward relative shifting movement to 45 embracingly clamp about the rail base flanges and capable of relative shifting movement in an outward direction to disengage and release the rails and means extending through the medial portion of said sections 50 for retaining the same against relative outward shifting movement.

2. A rail tie comprising a pair of telescopically associated inverted substantially

U-shaped sections, each of said sections having a recessed inner end and complementary recessed portions adjacent its outer end adapted to respectively coact with each other upon inward relative shifting movement to 55 embracingly clamp about the rail base flanges and capable of relative shifting movement in an outward direction to disengage and release the rails and means extending through the medial portion of said sections for retaining the same against relative outward shifting movement, said latter means comprising complementary slotted portions in 60 said sections and a wedge key insertable therethrough.

3. A rail tie comprising a pair of telescoping sections of inverted substantially U-shape 70 in cross section, each of said sections having a recessed portion adjacent its outer end presenting upstanding rail supporting edges and an overhanging inwardly disposed tongue, each of said sections having at its 75 inner end a complementary recessed portion presenting upstanding rail supporting edges and an outwardly projecting rail clamping tongue, the said sections adapted upon inward shifting movement to embracingly clamp about the rail base flanges and upon movement in the opposite direction to release the same and complementary slotted portions in the medial portion of each section and a locking key insertable 80 therethrough for retaining the sections in clamping relation to the rails and against relative outward shifting movement to disengage the same.

4. A rail tie comprising a pair of telescopic inverted substantially U-shaped sections, each section having an upper horizontal wall, depending side walls and outwardly turned horizontal flanges at the lower ends of the side wall, complementary recessed portions at the inner ends of each section and adjacent the outer end of each section providing rail base embracing and clamping means adapted upon relative inward shifting movement of the sections to clamp the 90 base flanges of the rail and adapted upon relative outward shifting movement to release the same, and means for retaining said sections in inwardly shifted clamping relation.

GEORGE B. COX,
